UNITED STATES PATENT OFFICE.

AUGUST KESSLER, OF NEW YORK, N. Y.

HANDLE FOR CANES, UMBRELLAS, OR PARASOLS.

SPECIFICATION forming part of Letters Patent No. 407,015, dated July 16, 1889.

Application filed April 4, 1889. Serial No. 306,026. (No model.)

To all whom it may concern:

Be it known that I, AUGUST KESSLER, of the city, county, and State of New York, a citizen of the United States, have invented 5 certain new and useful Improvements in Handles for Canes, Umbrellas, or Parasols, of which the following is a specification.

The object of my invention is to provide a new and improved head for canes, umbrellas, 10 or parasols, which is simple in construction, strong and durable, ornamental, and cheap.

The invention consists in a head for canes, umbrellas, or parasols, composed of a shell 15 formed of a series of interlocking spiral strips and a lining of soft solder or lead.

In the accompanying drawings, Figure 1 is a side view of my improved head for canes, umbrellas, or parasols. Fig. 2 is a vertical transverse sectional view of the same, showing 20 a different shape; and Fig. 3 is an elevation of a still different shape.

Similar letters of reference indicate corresponding parts.

The body A of the cane-head is composed 25 of a series of spiral strips *a*, which are wound on a mandrel in such a manner as to interlock—that is, one edge of each strip is bent up and engages the edge of the adjacent strip. Said body A can be made tapering or cylindrical. The strips are curved convexly on 30 their transverse axis, thus forming a series of spiral rounded ridges on the surface of said head or body. The several strips *a* composing the cane-head may be made of the same or of different metal, thus permitting of producing very handsome and ornamental effects by alternating metals of different colors—as, for instance, gold and silver, or gold and platinum. Some of the strips may be knurled or 35 may be provided with any other ornament. These ornaments are not engraved on the strips, but are produced by suitable rollers, thus permitting of making them at a very

low cost. The body thus formed of the interlocking spiral strips is provided with a cap 45 B and a bottom ring C. Into this shell a filling or lining D, of soft solder, lead, or any other suitable alloy, is poured, which serves to firmly unite the several spiral strips and the cap and bottom ring. My improved cane, umbrella, 50 or parasol heads may be made of any desired shape. The heads for umbrellas, canes, or parasols made heretofore and provided with spiral lines have been made of a single continuous piece and are very expensive for 55 the reason that they have to be chased and engraved by hand and only show one kind of metal. In my improved cane-heads the colors of metal may be varied as much as desired, as may also the strips having engraving or 60 chasing, or the number of strips and the pitch of the same.

Having thus described my invention, I claim as new and desire to secure by Letters Patent—

1. A cane-head formed of a series of interlocking spiral strips of metal, substantially as set forth.

2. A cane-head composed of a body, formed of a series of interlocking spiral strips of metal, a cap, and a base-ring, and a lining of 70 lead or soft solder which firmly holds together the spiral strips, cap, and base-ring, substantially as set forth.

3. A head for canes, umbrellas, or parasols, composed of a shell formed of a series of interlocking spiral strips and a lining of lead or soft solder, which holds the said strips together, substantially as set forth.

In testimony that I claim the foregoing as my invention I have signed my name in presence of two subscribing witnesses.

AUGUST KESSLER.
